CLAIM

The ornamental design for the wireless communication terminal, as shown and described.

DESCRIPTION

FIG. 1 is a front elevational view of the wireless communication terminal showing our new design;

FIG. 2 is a rear elevational view thereof;

FIG. 3 is a left-side elevational view of one side thereof;

FIG. 4 is a top plan view thereof;

FIG. 5 is a bottom plan view thereof;

FIG. 6 is a right-side elevational view of the other side thereof;

FIG. 7 is a cross sectional view taken along line 7—7 of FIG. 1 and omitting the inner mechanisms and electronic parts;

FIG. 8 is a rear perspective view thereof; and,

FIG. 9 is a front perspective view thereof, showing the terminal separated from the stand.
